UNITED STATES PATENT OFFICE.

BYRON B. GOLDSMITH, OF NEW YORK, N. Y.

DESIGN FOR A RUBBER ERASER.

SPECIFICATION forming part of Design No. 35,498, dated December 31, 1901.

Application filed October 10, 1901. Serial No. 78,281. Term of patent 7 years.

To all whom it may concern:

Be it known that I, BYRON B. GOLDSMITH, a citizen of the United States, and a resident of New York, in the county and State of New York, have invented and produced a new and original Design for Rubber Erasers, of which the following is a specification.

Figure 1 is a top view of a rubber eraser having the new design applied thereto. Fig. 2 is a side view; and Fig. 3 is an end view.

As shown in the drawings, the leading or material feature of my design consists in a block in the shape of a parallelepiped of greater length than width and greater width than thickness, having diamond-shaped depressions A on the top and bottom faces and V-shaped grooves B extending laterally across the end and side faces—that is, in a direction at right angles to the length of these said end and side faces. In the drawings these diamond-shaped depressions are indicated as inverted

pyramids with diamond-shaped bases, arranged contiguously in regular order. The bottom face of the block is a solid mass of these depressions, while the top face is divided into two equal parts by a longitudinally-extending centrally-located panel C, which is left plain or unornamented and may serve as a name-plate. The end and side faces of the block are entirely covered by parallel grooves B.

Having described my invention, what I claim, and desire to secure by Letters Patent, is—

The design for a rubber eraser, as herein shown and described.

In testimony whereof I have signed my name to this specification in the presence of two subscribing witnesses.

BYRON B. GOLDSMITH.
